UNITED STATES PATENT OFFICE.

JOHN EDGAR, OF ROCHESTER, MINNESOTA.

THILL-COUPING.

SPECIFICATION forming part of Letters Patent No. 605,666, dated June 14, 1898.

Application filed October 26, 1897. Serial No. 656,393. (No model.)

To all whom it may concern:

Be it known that I, JOHN EDGAR, of the city of Rochester, in the county of Olmsted and State of Minnesota, have invented certain new 5 and useful Improvements in Thill-Couplings, of which the following is a specification.

My invention relates to thill-couplings and antirattlers; and the object of the invention is to provide a thill-coupling which will allow 10 of the quick and easy attachment of the thills or tongue thereto and which will positively prevent the rattling of the thills.

A further object of the invention is to provide a thill-coupling of simple and few parts 15 in which there are no springs or yielding devices.

The invention consists generally in the combination, with the shackle adapted to receive the thill-iron and to hold the same against 20 movement in one direction, of a movable clamping member or jaw to also engage the thill-iron and hold the same against movement in the other direction; and the invention further consists in detail constructions 25 and combinations, all as hereinafter described, and particularly pointed out in the claims.

The invention will be more readily understood by reference to the accompanying drawings, forming a part of this specification, and 30 in which—

Figure 1 is a perspective view of a thill-coupling embodying my invention. Fig. 2 is a perspective view of the shackle. Fig. 3 is a perspective view of the movable member. 35 Fig. 4 is a perspective view of the thill-iron. Fig. 5 is a vertical section of the thill-coupling shown in Fig. 1. Fig. 6 is a vertical section illustrating a further modification of my invention.

As shown in the drawings, 2 represents the shackle, which is bound upon the axle and axle-stock by the usual clip 3. The shackle is provided with a preferably integral horizontal web 4 to receive the thumb-nut 5, which 40 is swiveled in said web 4. The sides of the shackle are provided with the vertical slots or notches 6 to receive the ends of the thill-eye-bolt 7. The bolt 7 is preferably formed integrally with the thill-iron 8, projecting from 45 the ends of the thill-iron in the form of studs or trunnions. To secure the bolt in the slots or notches 6, into which the bolt will natu-

rally drop when the thill-iron is placed on top of the shackle, I provide the movable member or clamping part 9, embracing the thill-iron and provided with slots or notches 10, extending at right angles to the notches 6 in the shackle. A screw 11 depends from the underside of the movable member 9 and may be raised or lowered by means of the swiveled 55 thumb-nut 5. When the member is drawn down, the eyebolt, as shown in Fig. 1, will be pinched between the upper arms of said member and the bottoms of the slots or notches 6. To increase the bearings of the clamp upon 60 the thill-iron, the upper arms of the clamp are provided with lateral extensions 9². The pressure upon the bolt to prevent the rattling or motion thereof may be varied by means of 65 the thumb-nut. The thumb-nut is arranged 70 as shown clearly in Fig. 5—that is, swiveled—in order that it may not be lost when the movable member is removed for any reason. It will be noted that the jaws of the movable member open rearwardly, and this feature of my device 75 possesses an especial advantage—namely, in putting on the thills or tongue the eyes are simply rested upon the tops of the shackles and drawn forward into the movable jaws, from which they cannot fall—while if the jaws 80 opened outwardly it would be necessary to use care in steering both eyes of the thills or tongue into the two shackles at the same time, which is a difficult feat.

In place of the vertical movable jaws or 85 member I may employ horizontal movable jaws, as shown in Fig. 6. In this case the shackle is provided with upwardly and rearwardly turning hooks or jaws 12, while the movable jaws are provided with vertical slots 90 13 and are adapted to slide upon the horizontal portion 14 of the shackle and to be tightened upon the thill-iron by means of a horizontal screw 15, which screw is fastened, so that it cannot move longitudinally in the lugs 95 16, depending from the under side of the shackle.

It is obvious that various modifications of my invention would readily suggest themselves to one skilled in the art, and I therefore do not confine my invention to the particular construction herein shown and described.

Having thus described my invention, I

claim as new and desire to secure by Letters Patent—

1. The combination, of the shackle, provided with slots or notches to receive the thill-iron, with vertically-movable clamping-jaws, having arms extending across the slots or notches in the shackle, and means for drawing down said movable member or jaw, substantially as described. 5
- 10 2. The combination, of the shackle, provided with the vertical slots or notches, with the jaw provided with horizontal slots or notches, a screw upon said movable jaw, and a swiveled nut upon said shackle, as and for 15 the purpose specified. 10
3. The combination, of the relatively-movable shackle and clamp, having opposed slots or openings to receive a thill-iron, with a swiveled member on one of said parts, engaging a 20 threaded part on the other for the adjustment thereof, substantially as described. 20
4. The combination, of the shackle, and the movable jaw, provided with vertically and rearwardly opening slots, with means for locking said movable jaw, substantially as described. 25
5. The combination, with a shackle having slots 6 and a swiveled nut 5, of a clamp 9 having slots 10 and screw 11 to engage said nut 5, and said slots 6 and 10 being substantially at right angles to each other and adapted to receive the studs or trunnions upon a thill-iron, substantially as described. 30
6. The combination, of a shackle, with a clamp, a screw for adjusting said clamp, said shackle and clamp having openings to receive a thill-iron, and having opposed portions to engage and hold said iron, and said clamp being adapted to support said thill-iron and raise the same out of engagement with said shackle, substantially as described. 35
7. The combination, of a shackle and clamp, having oppositely-extending thill-iron slots, and having opposed portions to engage and hold a thill-iron, means for adjusting said clamp, and said clamp being adapted to support said thill-iron and move it into engagement with said shackle and raise it out of engagement therewith, substantially as described. 40
8. The combination, of a shackle having slots to receive a thill-iron, and a movable bar or clamp, provided with slots extending oppositely with respect to those in the shackle, means for adjusting said movable clamp and said clamp being adapted to carry a thill-iron into engagement with said shackle and move the same out of engagement therewith, substantially as described. 45

In testimony whereof I have hereunto set 60
my hand this 20th day of October, A. D. 1897.

JOHN EDGAR.

In presence of—

C. G. HAWLEY,
A. F. HOLMES.
